UNITED STATES PATENT OFFICE.

DAVID L. WINTERS, OF PHILADELPHIA, PENNSYLVANIA.

INTERNAL-COMBUSTION ENGINE.

1,403,218.

Specification of Letters Patent. Patented Jan. 10, 1922.

Application filed September 3, 1920. Serial No. 407,694.

To all whom it may concern:

Be it known that I, DAVID L. WINTERS, a citizen of the United States, residing at Philadelphia, in the county of Philadelphia and State of Pennsylvania, have invented certain new and useful Improvements in Internal-Combustion Engines, of which the following is a specification.

This invention relates to internal combustion engines of the four-cycle type, and has for its primary object the incorporation of means in the construction thereof to increase the efficiency of their operation under throttled conditions.

15 Other objects of this invention will be specifically pointed out herein.

It is known that in the operation of four-cycle automobile engines under excessively throttled conditions, or when idling, that two 20 objectionable features become sufficiently noticeable as to impair the efficient operation thereof, as follows:

Under the circumstances of operation as above mentioned a partial vacuum is created 25 in the engine cylinders during the intake stroke, such vacuum increasing greatly toward the end of such stroke and causing lubricating oil to pass the pistons after the rings have become slightly worn, and to thus 30 form carbon deposits upon the spark plugs and valves, fouling the same and preventing proper operation thereof.

Under all conditions the inner walls of the cylinders are at a much lower temperature 35 than that of the charge during combustion, thus retarding the combustion and expansion of that portion of the charge coming in contact with the cylinder walls.

In order therefore to obviate the objectionable conditions of operation as above 40 outlined, the specific objects of this invention are as follows:

To provide a valveless outlet for that portion of the exhaust gases most heavily impregnated with lubricating oil, other than the usual outlet through the combustion chamber where the oil normally comes in contact with the valves and spark plugs.

To furnish to the cylinders at the end of 50 the suction stroke, exhaust gases and heat in inverse proportion to the volume of the explosive mixture therein. This will eliminate the period of inertia, or lack of power during the initial combustion of an excessively 55 throttled charge, and properly condition said charge for the most effective combustion

thereof, thus eliminating the present necessity of preheating such charges before the entrance thereof into the cylinder.

To position the exhaust gases furnished 6 the cylinders at the end of the suction stroke so that upon the compression stroke the explosive mixture will be advantageously positioned for ignition, and insulated from the walls of the cylinders by the presence of 6 such exhaust gases.

To minimize the passage of lubricating oil 7 past the piston and into the cylinder, by reducing the duration of the vacuum existing in such cylinders.

With the foregoing and other objects in view this invention consists in the peculiar construction and operation of the various related parts of a four-cycle internal combustion engine, as hereinafter described and 7 more particularly pointed out in the appended claims.

Referring to the accompanying drawings forming a portion of this specification, and in which the same reference numerals indicate the same parts wherever they occur,

Fig. 1 is a perspective view of an automobile engine assembly provided with an embodiment of this invention;

Fig. 2 is a view similar to Fig. 1, partially 8 broken away for clearness of illustration, and viewed in a direction opposite to that of Fig. 1;

Fig. 3 is a vertical section through a cylinder with the preferred form of this invention incorporated therein;

Fig. 4 is a horizontal section on line 4—4 of Fig. 3 and

Fig. 5 is a detail section of a portion of Fig. 3.

6 designates as a whole a multiple cylinder four-cycle internal combustion engine of any suitable type having the usual exhaust manifold 7. Communicating with the interior of the exhaust manifold 7 by passing through 1 the wall thereof is a pipe 8 having an inlet 9 formed at an angle with relation to the internal walls of the manifold 7, the apex 10 of such angle being located so as to present the greatest area of opening in a direction 1 opposite to the flow of exhaust gases within the manifold 7 as indicated by the arrow in Fig. 5, and for a purpose to be hereinafter explained.

The pipe 8 extends preferably over the engine cylinders and downwardly to an auxiliary manifold 11, which is in communica-

tion with a plurality of branch connections 12, each one of which connections 12 extends downwardly substantially parallel to the water jacket 13 and passes through the respectively adjacent cylinder wall 14 opening thereinto at a point 15, which opening is cleared by the piston 16 at its lowermost point on its downward stroke. The piston 16 is provided on the side adjacent the opening 15 with a baffle 17 which extends above and partially around the face of the piston at a relatively decreasing height thereto, the highest point 18 of such baffle 17 being directly opposite the opening 15.

The usual intake and exhaust valves are indicated at 19 and 20 respectively and are in communication with the intake and exhaust manifolds 21 and 7.

In operation the construction just described functions as follows, the operation of one cylinder being described in detail, it being understood that all cylinders of the engine operate identically therewith in their firing sequence.

Upon the firing of a charge within the cylinder, the piston 16 commences its descending stroke and continues thereupon until it has reached its downward limit when the opening 15 is cleared, at the same time the exhaust valve 20 has started to function in the usual manner to permit the exhaust gases to pass from the cylinder into the exhaust manifold 7. When the piston 16 has cleared the opening 15 the lower portion of the exhaust gases within the cylinder, due to the pressure thereof is exhausted through the opening 15 into its corresponding branch pipe 12 and into the auxiliary manifold 11, the manifold 11 being of such size as to permit the retention therein of a considerable proportion of the exhaust gases, and to prevent the exhaust gases passing directly from one cylinder into another, the remainder of such exhaust gases escaping through the opening 15 passing from the auxiliary manifold 11 into the pipe 8 and to the exhaust manifold 7.

On the following upward movement of the piston 16 on the normal exhaust stroke, the cylinder is cleared in the usual manner. The suction stroke of the piston 16 is then made in the usual manner until the piston has again cleared the opening 15 when, due to the partial vacuum existing in the cylinder, that portion of the exhaust gases retained in the auxiliary manifold 11 will flow through the proper branch connection 12 and into the cylinder through the opening 15, impinging against the high portion 18 of the baffle 17, this baffle forcing such exhaust gases to take an upward and circular direction within the cylinder. This upward direction given to these exhaust gases will cause them to form a layer adjacent the inner periphery of the cylinder wall 14 and relatively thicker on that

side of the cylinder adjacent the opening 15, thus forming an insulating and positioning means for the explosive mixture.

Upon compression this insulating layer will confine the explosive mixture in the most advantageous position for ignition and at the same time effectively insulate such explosive mixture from contact with the cylinder wall, and prevent the detrimental effect upon the combustion and expansion of such mixture, due to contact with such wall.

It will be seen that when idling or operating under light load the size of the charge and the richness thereof can be greatly reduced, since upon ignition the pressure due to expansion is at once communicated to the piston through the medium of the compressed exhaust gases surrounding the charge. Also, these compressed exhaust gases will impart a driving force to the piston throughout the entire stroke instead of only a part thereof, and greatly reduce the vibration of large four cylinder engines.

Obviously, by thus insulating the explosive mixture from the walls of the cylinders, a great saving in heat is effected and utilized in propelling the vehicle, while the necessity for cooling the cylinders will be greatly decreased, and the efficiency of the lubricating oil greatly increased.

Considerable variation of the details as described herein may be resorted to without departure from the spirit of the invention which is to be construed in the light of the following claims.

What I claim is:

1. The method of operating a four-cycle internal combustion engine to maintain a uniform compression therein, which consists in discharging a portion of the exhaust gases into an exhaust conduit of said engine subject to atmospheric pressure, admitting an explosive mixture to a cylinder of said engine, and then adding a portion of the exhaust gases under atmospheric pressure to said explosive mixture before ignition of such mixture.

2. In the operation of a four-cycle internal combustion engine, the method which consists in first admitting the explosive mixture thereto, and then admitting a portion of the exhaust gases in such manner as to substantially surround the explosive mixture whereby to insulate the said explosive mixture from the cylinder walls of said engine.

3. In a four-cycle internal combustion engine, the combination with a cylinder thereof, of means to maintain a uniform compression therein comprising means for discharging a portion of the exhaust gases into an exhaust conduit of said engine open to atmospheric pressure, means for feeding an explosive mixture to a cylinder of said engine, and means for adding a portion of the exhaust gases under atmospheric pressure to said ex-

plosive means in the cylinder before the ignition of such mixture.

4. The method of operating a four-cycle internal combustion engine to maintain a uniform compression therein, which consists in discharging a portion of the exhaust gases into an exhaust conduit of said engine open to atmospheric pressure, admitting an explosive mixture to a cylinder of said engine, and
- 10 then adding a portion of the exhaust gases under atmospheric pressure to said explosive mixture before ignition of such mixture.

5. In a four-cycle internal combustion engine, the combination with the cylinder thereof, of means for supplying said cylinder with an explosive mixture, means for supplying said cylinder with exhaust gases, a piston in said cylinder, and means carried by said piston to position the said exhaust gases in the cylinder against the walls thereof. 15

In testimony whereof I affix my signature hereto.

DAVID L. WINTERS.
